UNITED STATES PATENT OFFICE

SCOTT M. ABBOTT, OF CHICAGO, ILLINOIS, ASSIGNOR TO LOUIS J. LOENNEKE AND HERMAN BOCK, BOTH OF CHICAGO, ILLINOIS

VENDING MACHINE

Application filed March 19, 1930. Serial No. 437,120.

This invention relates to improvements in vending machines and more particularly to package vending machines of the coin operated type. One object is to provide a vending machine wherein a stock of package goods is carried in such manner that the individual packages are selectively obtainable at the will of the purchaser or operator. A further object is to provide a machine of this type that is theft proof. A still further object is to provide a vending machine that is compact in assembly, attractive in appearance and one wherein the contents are always visible so that an inventory thereof can be instantly made and at the same time the goods thus advertised to the public.

A still further object is the provision of a vending machine that is positive and efficient in operation, durable in use and one wherein the actuating mechanism is so positioned as to be readily accessible to a mechanic familiar with the machine so that repairs, replacements or adjustments can be made without difficulty when necessary. With the foregoing and other objects in view the invention consists in the combination and arrangement of parts to be herein-after fully described, pointed out in the claims and illustrated in the accompanying drawings which form a part of this application for patent and in which—

Fig. 1 is a face view of the vending machine.

Fig. 2 is a side view of the same.

Fig. 3 is a fragmentary view of Fig. 2 illustrating the bayonet slot in the cover plate to permit its attachment to the drum.

Fig. 4 is a fragmentary rear view of the cover plate enlarged.

Fig. 5 is a fragmentary view of the machine in elevation, the face or cover plate being removed.

Fig. 6 is a fragmentary vertical sectional view through Fig. 5.

Fig. 7 is a fragmentary plan view of the stationary drum.

Fig. 8 is a vertical sectional view through the stationary drum showing the interior mechanism.

Fig. 9 is a fragmentary view of the station-

ary drum and interior mechanism in rear elevation.

Fig. 10 is a view similar to Fig. 8 taken on the opposite side of the drum partition.

Fig. 11 is an enlarged vertical sectional view taken on the line 11—11 of Fig. 10.

Fig. 12 is a similar view taken on the line 12—12 of Fig. 10.

Fig. 13 is a fragmentary view of Fig. 10 with the adjustable parts in an altered position.

Like reference characters denote corresponding parts throughout the several views.

The present invention comprises but relatively few moving parts which include a rotary package carrier disposed between the casing periphery and a central stationary drum, this drum being provided with a partition, vertically disposed and located off center, that is, to one side of the center of the drum and to the opposite lateral faces of said partition the actuating mechanism is secured. Should repairs or replacements be necessary this partition and its appurtenances can be readily removed from the drum and worked upon without disturbing the rest of the mechanical assembly. The machine may be provided in the counter type, adapted to stand upon a table, counter or like support, or it may be of the wall type, adapted to be suspended from a hook secured in a wall.

The reference numeral 1 denotes the casing having the back 2 and provided with the several bolts 3 adapted to be received into the bayonet slots 4 formed in the flange 5 of the cover or face plate 6 whereby to releasably secure said casing and cover together.

A lock 7, key operated, is carried by the casing whereby the cover 6 may be securely fastened thereto.

A bearing 8 secured centrally to the back 2 receives one end of a rotary shaft 9 that extends diametrically of the casing and into the shank of the knob 10 that is arranged centrally of the face plate 6, a pin 11 extending through the shaft 9 having its ends received in the transverse groove 12 of the shank of the knob whereby rotation of said knob will be transmitted to the shaft. Fast upon said shaft 9 contiguous to the bearing 8 is the

spider 13 to the outer ends of which the angular carrier 14 is secured that is formed with the flange 15 disposed at a right angle thereto, said carrier and flange carrying the V-shaped partitions 19, spaced apart to separate the packages of goods to be dispensed, one package or parcel being placed between any two successive partitions. The goods arranged in the carriage 14, 15 are visible to the public through the windows 16 arranged in a circle, spaced apart, in the cover plate.

Fast to the spider 13 and centered upon the shaft 9 is a locating and locking disc 17 formed peripherally with the elongated teeth 18, the free ends thereof being pointed, the successive teeth being spaced equal distances apart and being equal in number to the partitions 19.

An open faced stationary drum 20 of circular shape has its back 21 perforated centrally to permit passage of the rotary shaft 9, said drum being supported by the three angular arms 22 that connect it to the casting 1, said drum being formed with a large transverse package delivery perforation 23 that registers with two spaced parallel longitudinal perforations 24 and with a pair of spaced oppositely disposed guide brackets 25 for the shank 26 of the gate 27 that normally closes the said package delivery perforation 23, said gate being formed with the spaced parallel guide ribs 28 adapted to ride in the said perforations 24 and the shank being formed with a longitudinally disposed central guide rib 29 that, as the shank and guide move back and forth along the inner periphery of said drum, rides through a clearance recess 30 formed in the upper end of the vertical partition 31 that spans said drum, off center, said partition being secured by bolts 31a to said drum and formed at its ends with feet 32 that are bolted or riveted to the drum.

Spaced upwardly from the lower end of the partition 31 and secured by rivets 33 to one face thereof is a metal guide or cover plate 34 which is spaced outward slightly from the partition, throughout the greater part of its extent, to provide a guide for certain movable parts to be hereinafter described, one portion 35 of said guide being contiguous to the lower opening in the conventional type of coin receiver 36 the mouth of which is in registry with the coin opening 37 in the cover plate 6.

A slug chute 38 extending diagonally through a perforation in the partition 31 is disposed beneath a slug-discharge opening in the coin receiver to receive such slugs as may be discharged therefrom, said chute 38 extending through a perforation 41 in the metal shield 39 and terminating in the contracted discharge end 40 from which the slug is precipitated outside the machine through the opening 42 in the cover plate.

A guard plate 43 secured to the contracted end of the chute and riding against the partition 31 protects the mechanism assembled upon the partition from being tampered with, jimmied or pried out of place by mischievous persons seeking to fraudulently obtain the contents of the machine. A guard disc 43a secured to the partition 31 extends over the chute 40 also as a protection.

Fulcrumed upon a bolt 44 to the partition 31 is the lever 45 that extends out through a perforation 46 in the drum back 21 and through an elongated perforation 47 in the cover plate. A return spring 49 connected by pin 50 to the lever 45 is connected at its upper end to the partition 31, said spring engaging the lever between its fulcrum point and its outer end.

Between the fulcrum and inner end of the lever the same is formed with an elongated slot 51 in which a sleeve 52, provided with a washer 53, rides; a rod 54 having its lower end bent to pass into said sleeve to which it is made fast, said sleeve 52 extending also through a vertical slot 55 in the partition and operatively engaging a riser plate 56 that slides over the opposite face of said partition 31 between the same and the guide 34, the upper end of said riser plate is recessed to provide one narrow extreme termination 57 and a relatively lower upper edge 58, the latter edge being normally disposed immediately below a circular perforation 59 spaced immediately above the upper end of the said vertical slot 55, said perforation 59 normally receiving the bevelled end of a lug or spur 60 carried at one end of a flat spring 61 terminally secured by the rivet 62 to the cover guide 34 and serving as a guide spur for the coin when the same is in position upon the raiser plate 56.

Referring again to the rod 54, that rides upward from the sleeve 52, it has fast thereupon a stop collar 63 that receives one end of an expansion coil spring 64 that encompasses said rod and also encompasses a metal sleeve 65 that is loose upon said rod, said sleeve being of less length than the spring in the normal position of the same, the upper end of said spring abutting a block 66 formed with a reduced portion 67 that extends through a vertical slot 68 in the partition 31 and is fast to a flat plunger plate 69 that rides over the face of the partition remote from block 66, another vertical slot 70 in the partition 31 being spaced from the slot 68 and parallel thereto and providing clearance for the lower end or heel 71 of the slightly curved gate-control lever 72 fulcrumed upon the pin 73 to a partition 74 which is punched out, all but one edge, from the metal guide 34, an angular arm 75 fast to the forward end of said gate-control lever being connected by the lever-return spring 76 to the coin receiver 36.

- The forward extremity of the lever 72 is formed with the bifurcation 77 to permit its operative engagement with the inwardly bent end 78 of the gate shank 26.
- 5 The said lever 45 has its inner end bent laterally, with respect to the partition 31, and terminating in an integral block 79 which is recessed to receive one end of a finger 80 parallel with the lever axis and terminating beyond the adjacent open end of the drum 20. A pawl 81 pivoted to one face of the block 79, at right angles to the finger 80, is engaged by the spring 82 and adapted to work over the rack 83 formed upon the contiguous face of the partition 31. In the normal position of the lever 45 the pawl 81 is out of engagement with the rack 83 but as the lever is moved upon its fulcrum by depressing its outer end the pawl rides over the teeth of said rack and, until it passes beyond the upper end of the rack, prevents a return movement of the lever from any adjusted position. The lever is yieldingly retained in said normal position by the spring 49.
- 10 The lower edge of the plate 69 is somewhat irregular and comprises a finger 84 that rides over the partition 31 in a position offset from the top edge 57 of the riser 56, with a bevelled lower edge portion 85 that runs from said finger obliquely upward and terminates in the arcuate recess 86, a small vertical slot 87 in said plate rising from the edge 85, said plate 69 being formed also with a stop lug 88 contiguous to the heel 71 of lever 72 for abutment with the lower end of the slot 70 to arrest the further downward movement of the plate 69 and its connections.
- 15 An angular bracket 89 secured to the partition 31 has the lower end of a locking lever 91 secured thereto by pin or rivet 90, the pin being somewhat smaller than the perforation in the lever so that a limited movement or play of the lever, vertically, is possible, said lever being formed adjacent its pivoted end with a bevelled spur 92 that is yieldingly projected through the said slot 87 in the plunger plate 69 and through a slot 93 in the partition 31, with which said slot 87 registers; said lever 91 being formed further with the spurs 94 and 95 both of which normally project through the elongated slot 96 in the partition 31, said slot 96 being of greater length than the distance from the lower edge of the spur 94 to the top edge of spur 95 so that clearance is provided for a certain play or degree of movement of the lever relative to the partition with the lever in the position shown in Fig. 11.
- 20 A spring 97 bears against the lever 91 to yieldingly retain it in adjusted position relative to the partition 31, one end of said spring being secured to said partition. A link 98 is pivotally secured by pin 99 to the

partition 31, one end of said link being engaged and yieldingly retained in normal position by a contractile spring 100 secured by pin 101 to the partition, the end of said link remote from said spring carrying a round pin 102 disposed in an arcuate slot 103 formed in said partition, said pin being yieldingly retained in one end of said slot in engagement with the arcuate recess 86 in the plate 69 through the action of the spring 100. A coin box 104 is secured to the partition 31 beneath, or encompassing, a recessed portion 105 in the guide plate 34 through which the coin is ejected after having served to operate the machine in a manner to be hereinafter described. In the drawings the coin box is shown materially smaller than it is intended to be. This is to prevent obscuring certain portions of the operating mechanism.

The coinbox is provided with a gate 106 and said box is formed with a cut out portion 107 to provide clearance for spring 61.

The operation is as follows: The operator surveys the contents of the machine through the windows 16. Any package selected must be brought to a position visible through the window 16 indicated by the arrow 108, Fig. 1. This is done by rotating the carriage 14, 15 carrying the packages or goods. He now drops a dime in the coin receiver 36 which dime passes through the chute or guide portion 35 and then through a passageway formed by the partition and the guide 34. The dime is visible as it passes, or drops, past the corner 109 of the large cut out portion of the guide wall 34, the passageway then causes it to travel immediately below the pin 102 and to lodge between the guide and partition upon the end 57 of plate 56, resting against the finger 84 and immediately below the recess 105 in guide plate 34. The dime travels over this distance to this location almost instantly. To release the parcel the operator now manually depresses the outer end 110 of the lever 45. This lever will move the finger 80 upward and between two of the elongated teeth 18 which will lock the spider 13, disc 17 and carriage 14, 15 and position the package sought directly in alignment with the delivery opening 23 in the drum 20. At the same time the lever 45 will raise the rod 54, the spring 64 pressing against the block 66 will cause the same to raise the plunger plate 69 to which the reduced end 67 of block 66 is secured. The dime will be raised by the riser 56 into proximity to the bevelled edge 85 of plate 69 and as that plate is raised relative to the locking lever 91 the dime will encounter the bevelled spur 92 thereof and thrust it and the lever outward upon pivot pin 90.

The spur 94 will then have been thrust out of the path of the plunger plate 69 which plate can then travel to the extreme upward end of its path without interference from the

lever or detent 91. The upward movement of the plate 69 unhampered causes a corresponding downward movement of the bifurcated end 77 of the lever 72 bringing with it the gate shank 26 and gate 27 thus uncovering the package delivery perforation 23 and permitting the package to pass therethrough by gravitation and to fall or strike against the shield 39 and lie at the delivery opening 42 in the cover plate within the drum from which it may be removed by the operator. While the inner end of the lever 45 rides upward the pawl 81 will pass over the rack 83 and beyond same. While it is engaging the rack it will prevent a return movement of the lever should the operator not use force enough to cause it to travel out of rack engagement. From any locked position of the pawl and rack the lever can be further moved until the full sweep of the lever is made and the rack and pawl separated.

When the pawl passes out of engagement with the rack the lever and all connections are free to return to normal position and this action will be accomplished through the operation of the springs 49, 64 and 76. After each return of the lever the moving parts are ready for another operation. When the dime rises into the opening 105 in the guard plate it also forces the pin 102 out of its path by this movement. Should a person intentionally or inadvertently drop two dimes in the machine at the same time, both may pass through the dime passageway. One dime will stop in operative position upon the edge 57 of the riser, as previously described, and the other dime will abut the first one in a position supported by the spur 60.

As the lever 45 is operated the first dime will force the second one to one side, the first dime releasing a package and then dropping into the coin box. The second dime will drop immediately thereafter into operative position ready for a second operation of the discharge mechanism so that, if the operator positions another package before the discharge opening 23 he will not lose his second dime but will receive a second package for it.

In the event that no dime is placed in the coin receiver the spur 92 of the lever 91 will not be thrust outward and consequently the plunger plate 69 will not move upward far enough to cause it to actuate the lever 72 sufficiently to move the gate 27 from over the discharge opening 23. When the upward movement of the plunger plate 69 is blocked by the spur 94 the upward movement of the block 66 is likewise limited but the rod 54 rides up the full extent of its stroke, passing freely through the block, the block merely compressing the spring 64 to compensate for the relative movement of said rod 54. Idle manipulation, then, of the lever by a person, without dropping a dime into the coin receiver will but compress the spring 64, move

the plunger plate 69 and lever 72 but a portion of their full sweep, or inoperatively, and fail to displace the gate 27 from the opening 23. When the upper end of the plunger plate rides against the spur 94, as it will if a dime has not moved this lever outwardly from the partition, the lever 91 will bind against the top edge of the slot 96 and the mechanism will not function operatively. The top spur 95 serves as a guide and retaining spur to prevent detachment of the lever from the partition. Adjusting nuts 111 are arranged upon the threaded upper end of the rod 54 to adjust the same relative to the spring 64 so that the proper compression or tension of the latter member may be provided.

What is claimed is:—

1. In a package vending machine, a casing, a stationary drum therewith formed with a package delivery perforation, a gate normally closing said perforations, a rotary multiple package carrier encircling said drum and adapted to deliver its packages singly through said drum perforation in the open position of the same, a partition in said drum provided with openings, a detent fulcrumed thereto and having projections extending through said openings, means yieldingly engaging said detent, a riser plate carried by said partition, a plunger plate carried by said partition, one of the projections on said detent being in the path of said plunger plate, said plunger plate being spaced from said riser plate to admit a coin between said plates whereby motion of said riser plate will cause the coin to engage the other of its projections on said detent to release the plunger plate, a lever operatively engaging said riser plate, a lever connecting said plunger plate and gate, and connection between said plunger plate and riser plate whereby movement of the latter is but partially transmitted to said plunger plate normally.

2. In a package vending machine, a casing, a stationary drum therewith formed with a package delivery perforation, a gate normally closing said perforation, a rotary multiple package carrier encircling said drum and adapted to deliver its packages singly through said drum perforation in the open position of the same, a partition in said drum provided with openings, a detent fulcrumed thereto and having projections extending through said openings, means yieldingly engaging said detent, a riser plate carried by said partition, a plunger plate carried by said partition, one of the projections on said detent being in the path of said plunger plate, said plunger plate being spaced from said riser plate to admit a coin between said plates whereby motion of said riser plate will cause the coin to engage the other of the projections on said detent to release the plunger plate.

plate, a stop lug carried by said plunger plate normally engaging said partition, a lever fulcrumed to said partition and operatively engaging said riser plate, a block carried by said plunger plate, a rod extending freely through a perforation in said block and connected to said lever, a stop collar upon said rod, a sleeve loose upon said rod between said stop collar and block, a spring encompassing said rod and sleeve and abutting said stop collar and block, said spring normally being of greater length than said sleeve, and a lever connecting said plunger plate and gate.

- 15 3. In a package vending machine, a casting, a stationary drum therewithin formed with a package delivery perforation, a gate normally closing said perforation, a rotary multiple package carrier encircling said drum and perforation in the open position of the same, a partition in said drum provided with openings, a detent fulcrumed thereto and having projections extending through said openings, means yieldingly engaging said detent, a riser plate carried by said partition, a plunger plate carried by said partition, one of the projections on said detent being in the path of said plunger plate, said plunger plate being spaced from said riser plate to admit a coin between said plates whereby motion of said riser plate will cause the coin to engage the other of the projections on said detent to release the plunger plate, a lever fulcrumed to said partition and operatively connected to said riser plate, a lever connecting said plunger plate and said gate, and a stop lug carried by said plunger plate and normally engaging said partition.
- 40 In testimony that I claim the foregoing as my own I have hereto affixed my signature.

SCOTT M. ABBOTT.
